US0D1043913S

(12) **United States Design Patent** (10) **Patent No.:** **US D1,043,913 S**
Jia (45) **Date of Patent:** **** Sep. 24, 2024**

(54) **THREE-PATTERNS HIGH-PRESSURE FOAM CANNON**

(71) Applicant: **Hangzhou Weirran Machinery Co., LTD**, Hangzhou (CN)

(72) Inventor: **Qunwei Jia**, Hangzhou (CN)

(73) Assignee: **HANGZHOU WEIRAN MACHINERY CO., LTD**, Hangzhou (CN)

(**) Term: **15 Years**

(21) Appl. No.: **29/852,956**

(22) Filed: **Sep. 12, 2022**

(30) **Foreign Application Priority Data**

Jul. 6, 2022 (CN) 202230425985.8

(51) **LOC (14) Cl.** **23-01**

(52) **U.S. Cl.**

USPC **D23/225**

(58) **Field of Classification Search**

USPC D23/202, 213, 225

CPC B05B 9/08; B05B 9/0816; B05B 7/2443;

B05B 7/2408; B05B 7/2421

(57) **CLAIM**

The ornamental design for a three-patterns high-pressure foam cannon, as shown and described.

DESCRIPTION

FIG. 1 is a perspective view of a three-patterns high-pressure foam cannon showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

1 Claim, 8 Drawing Sheets
